MACHINE FOR VULCANIZING A SIDEWALL STRIP ON TIRE WALLS

William Odell Dismuke, 289-91 Sunflower Ave.,
Clarksdale, Miss.

Filed Apr. 30, 1963, Ser. No. 74,672

Term of patent 14 years

(Cl. D54—13)

FIG. 3.

FIG. 4.

FIG. 1 is a side perspective view of the present machine for vulcanizing a sidewall strip on tire walls.

FIG. 2 is a top plan view of said machine.

FIG. 3 is a side elevation of said machine, and

FIG. 4 is a cross sectional view taken on line 4-4 of FIG. 3.

The tire and hose shown in broken lines in the several views are disclosed for illustrative purposes only.

I claim:

The ornamental design for a machine for vulcanizing a sidewall strip on tire walls as shown and described.
